(57) **CLAIM**

The ornamental design for a helmet tether anchor snap, as shown and described.

DESCRIPTION

FIG. 1 is a front perspective view of a helmet tether anchor snap showing our new design;

FIG. 2 is a left side elevational view thereof;

FIG. 3 is a bottom plan view thereof;

FIG. 4 is a rear elevational view thereof;

FIG. 5 is a front elevational view thereof;

FIG. 6 is a right side elevational view thereof; and,
FIG. 7 is a perspective view thereof, showing the snap on a helmet.

The broken line drawings of the helmet are for illustrative environmental purposes only and form no part of the claimed design.
